Inventor:

George A. Lathrop

UNITED STATES PATENT OFFICE.

GEORGE A. LATHROP, OF EAST SAGINAW, MICHIGAN.

METALLIC WINDOW-BLIND.

Specification of Letters Patent No. 26,438, dated December 13, 1859.

To all whom it may concern:

Be it known that I, GEORGE A. LATHROP, of East Saginaw, in the county of Saginaw and State of Michigan, have invented a new and Improved Shutter or Blind for Windows, &c.; and I do hereby declare that the following is a full, clear, and exact description of the same, reference being had to the accompanying drawing, forming a part of 10 this specification, in which—

Figure 1, represents a transverse vertical section of my invention. Fig. 2, is an inside view of the same. Fig. 3, is a horizontal section of the same.

15 Similar letters of reference in the three figures indicate corresponding parts.

The object of my invention is to produce a shutter or blind that is at once simple, cheap, easily operated and fire-proof; and it consists in combining with a metallic plate 20 provided with slots and water-sheds or slats a slotted slide in such a manner that the light may be admitted or excluded at pleasure, and that a fire-proof blind is produced.

25 To enable others skilled in the art to make and use my invention I will proceed to describe it.

A metal plate A, is furnished with slots *a*, and intermediate spaces *b*. In order to form 30 the slots, incisions are made on three sides, and the metal is now bent up to an angle of about 35 degrees, more or less, so as to form watersheds or slats *c*, similar to the slats of common wooden blinds. The form of these 35 slats, and the manner in which they are bent is clearly shown in Figs. 1, and 3.

I do not intend to confine myself however to the precise form of the slots and slats represented in the drawing as the same can be made in various forms with equal advantage. 40

The edges of the plate A, are turned over so as to form grooves *d*, as clearly shown in Fig. 3, and these grooves form guides for a slotted slide B. This slide is made of a plain piece of sheet metal and the slots *e*, in 45 the same, are cut out so as to correspond in size and in the distance in which they are apart, with the slots *a*, in the plate A, and the spaces between said slots are large 50 enough to cover up the slots *a*, if the slide is brought in the proper position. Thus when the slide B, is brought in such a position, that the slots *e*, register with the slots *a*, light and air is admitted, but if the spaces 55 between the slots *e*, are brought to cover the slots *a*, the blind is perfectly shut and rendered fire-proof.

It will be easily understood how, by a simple device the slide may be made to 60 move up and down and how it can be arrested in the required position.

What I claim as new and desire to secure by Letters Patent, is,

The arrangement of the plate A, with 65 slots *a*, slats or watersheds *c*, and grooves *d*, in combination with the slotted slide B, substantially as and for the purpose specified.

GEORGE A. LATHROP.
